UNITED STATES PATENT OFFICE.

CHARLES McVEETY, OF CHELTENHAM, PENNSYLVANIA.

HOT-AIR HEATING SYSTEM.

1,393,301.

Specification of Letters Patent. Patented Oct. 11, 1921.

Application filed February 24, 1921. Serial No. 447,385.

To all whom it may concern:

Be it known that I, CHARLES McVEETY, a citizen of the United States, residing at Cheltenham, in the county of Montgomery 5 and State of Pennsylvania, have invented certain new and useful Improvements in Hot-Air Heating Systems, of which the following is a specification.

My invention relates to improvements in 10 heating system and more particularly to hot air heating systems.

An object of my invention is to provide a re-circulating system of hot air heating based on the principle of a hot water circulating system employing feed and return pipes. The system is based on the principle 15 that to fully and economically heat a dwelling it is necessary to keep the air in constant circulation. When warm air is discharged 20 into a room at the registers at 140°, it circulates through the room or rooms giving off its heat units and due to transmission of heat through glass, exposed walls, etc., this 25 temperature of the incoming hot air is reduced to about 65°. The air is then returned to the heater through return pipes therefor and is refreshed with outside cool air through ducts leading to the base of the 30 heater. The air is then reheated and recirculated.

A further object of the invention is to provide a system of hot air heating, combining the conventional pipe hot air system 35 with outside cool air ducts, an air recirculating system using the rooms as radiators and a pipeless or one pipe system.

A further object of the invention is the provision of novel damper means whereby either of the foregoing systems, separately 40 or in combination, may be utilized to the advantage of the user.

A further object is to provide a heating system by which hot air may be directed into a single room or led to a number of 45 rooms, by a novel arrangement of parts.

With these and other objects in view the invention resides in certain novel features of construction and in unique combinations of parts to be hereinafter fully described 50 and claimed, the descriptive matter being supplemented by the accompanying drawings, wherein:

Figure 1 is a diagrammatical front elevational view, partly in section, of my heating system installed in the basement and three 55 floors of a building;

Fig. 2 is a front elevational view of the heater and its connections;

Fig. 3 is a sectional plan view of the heater on line 3-3 of Fig. 2;

Fig. 4 is a detail sectional view of the oblique angular member connecting an air duct to the first floor register structure, with a damper positioned at an angle therein;

Fig. 5 is a detail sectional view of the 65 single valve damper used, the same illustrating the use thereof to partially close a hot air supply pipe; and

Fig. 6 is likewise a detail sectional view of the single valve damper used, the same 70 illustrating the use thereof to close a hot air supply pipe.

Like numerals denote like parts throughout the drawings.

Referring to said drawings in detail, the 75 numeral 10 designates a heater of a conventional type used for hot air heating purposes having an outer shell or casing and an inner shell or radiator and an air thoroughfare or passageway therebetween, provided with a 80 base 11, a bonnet 12 and a main outlet pipe 13 to a first floor register 14. From said bonnet 12, hot air outlet pipes 15, 16, 17 and 18 are provided in the usual manner for conveying hot air from said heater 10 to various rooms. The extensions 19 and 20 of said 85 hot air pipes 16 and 17 are shown in Fig. 1 extending vertically through the partition walls of rooms in the usual manner to supply hot air to rooms on the second and third 90 floors, registers 21, having dampers 25 controlled by members 22 of said registers 21 being provided to regulate the volume of air to be admitted to the individual rooms of the building, or to pass therefrom. Pipes 95 15 and 18 may in like manner be connected with other rooms in the house.

Cool air ducts 29 and 30, preferably rectangular in form are provided paralleling either side of the outer casing of the heater 100 10 and in spaced relation thereto, and are secured by suitable connections to openings in the base 11 of said heater. Oblique angular members 29' and 30' connect the upper portions of said ducts 29 and 30 to 105 the first floor register structure as illustrated. By means of said ducts 29 and 30 cool air is admitted to the heater 10.

Pipes 23 and 24 are connected to the openings 31 and 32 in the oblique angular members 29' and 30' of the cool air ducts 29 and 30, as illustrated, and extend substantially

horizontally and then vertically by means of the connecting pipes 23' and 24' in the side or other walls of the building, and are provided with like dampers 25 at the various 5 floor levels to admit the cool air circulating near the floor levels of said rooms to said pipes, whereby the cool air descends through said pipes and ultimately enters the heater 10. Connecting pipe 23² and 23³ may like-

10 wise be extended to other rooms in the house.

A register 28 is provided, as shown, to admit cool air from the outside to the pipe 24 through the connecting pipe 24² whereby the outside air may be admitted directly to the 15 duct 29, or in conjunction with the cool air descending from the upper rooms, the ingress of air from said register 28 being regulated by a damper 28' in the pipe 24. Similar means are employed to admit outside air 20 to the opposite duct 30.

Dampers 34' are provided to regulate the ingress of cool air to the ducts 29 and 30. Said dampers 34' have the extending handles 34 whereby they may be positioned in 25 any desired plane. Dampers 35 are positioned in each of the hot air pipes 15, 16, 17 and 18.

In operation: In use as the usual hot air pipe heating system the pipes 15, 16, 17 and 30 18 are connected up as above described, or such of said pipes as may be required to heat the rooms desired; the heat ascends through said pipes and the extensions thereof as indicated by the arrows and is admitted there- 35 from to the various rooms by means of the registers 21 and the dampers 25. Cool air is admitted from the outside by means of a register 28, through the pipe 24² to the extension 24 from the duct 29 through which 40 it gains admission to the furnace 10 and mixes with the heated air therein, aiding circulation and freshening the air; outside cool air is admitted to the opposite duct 30 in a similar manner by similar means.

45 In use as a recirculating system the pipes 15, 16, 17 and 18, or such of them as are required, are connected as aforesaid, and the heat ascends therethrough and through the branches thereof, as indicated by the ar- 50 rows; cool air descends from the upper floor levels through the connecting pipes 23, 23', 24 and 24', as indicated by arrows in Fig. 1, and the connections 31 and 32 to the ducts 29 and 30, from which said ducts 29 and 30

55 said cool air enters the heater 10 adjacent the base thereof and circulates through the air thoroughfare in said heater between the radiator and outer casing thereof and is heated by the radiation from said heater and 60 mixes with the hot air in said thoroughfare. The pipes and their branches returning the cool air to said heater, as aforesaid, have the combined area of the air spaces or thoroughfares through said heater 10. It will

65 be noted that a space is provided between

the outer casing of the heater and the ducts 29 and 30. This is to prevent the cool air on its return to the heater from being heated by radiation therefrom until said air has actually entered said heater. Cool air may be 70 admitted from outside to the ducts 29 and 30, as hereinbefore described, to freshen the air in said ducts to aid circulation, if de- sired.

In use as a pipeless or one pipe hot air 75 heating system, the dampers 35 in the hot air pipes 15, 16, 17 and 18 are closed; the damper 33 is opened; the dampers 34' in the oblique angular members 29' and 30' are positioned so as to check the ingress of air 80 through the openings 31 and 32 and their connections. The hot air thereupon ascends through the pipe 13 and the register 14 and the cool air is returned to the heater between said pipe 13 and the register structure 85 through the angular members 29' and 30' and the ducts 29 and 30 and circulates through said heater as hereinbefore de- scribed.

By closing the damper 33, whereby it acts 90 as a closure or top to the bonnet 12, and opening the dampers 35 in the hot air pipes 15, 16, 17 and 18, the hot air ascends to the upper floors and by positioning the dampers 34' to check the air descending from the reg- 95 ister 14 and to admit air through the openings 31 and 32, as hereinbefore described, the cool air is returned to the heater and warmed and circulated. This method of recirculating air has been found in practice 100 to positively heat a dwelling in all parts thereof with less coal consumption.

By setting the dampers 25 at angles all 105 rooms can be supplied with heat at the same time. By setting the damper 33 at an angle both the first and upper floors can be sup- plied with heat at the same time. The dampers 34', can be positioned to secure cool air from the register 14 and the circulating air pipes 23 and 24 and from the outside, or 110 from all these sources at the same time.

A deflector 36 may be used in connection with the pipeless or one pipe system to deflect the hot air ascending through the radiator 14 to two separate first floor rooms, by 115 positioning the register 14 beneath the partition wall of said rooms as illustrated in Fig. 1 and inserting the V-shaped deflector 36 in a recess cut in said partition.

The dampers 25, 28', 33, 34' and 35 are all 120 of a similar conventional single valve type and can be positioned in the hot and cool air pipes to regulate the circulation of both the hot and cool air as may be desired. Said dampers are particularly illustrated in Figs. 125 5 and 6 of the drawings. In Fig. 5 the damper 25 is shown partly closing the hot air supply pipe (for example the pipe 20) whereby a portion of the ascending heated air enters a room through the register 21 and the re- 130

maining portion continues its ascent, while in Fig. 6 the damper 25 is shown entirely closing the hot air supply pipe so that all the ascending air must obviously pass 5 through the register 21. In this way the ascending hot air may be admitted or retarded or partly admitted and partly retarded from a particular room or rooms. In Fig. 10 4 the valve portion 34' is shown positioned so as to admit cool air to the duct 30 from both the opening 32 and the register 14.

From the foregoing description, taken in connection with the accompanying drawings, the construction, means of operation 15 and the numerous advantageous features of the invention will be readily understood without requiring a more extended explanation.

Although, in the drawings, I have shown 20 certain specific details of construction and in the preceding have described such details, it is obvious that I need not be limited thereto otherwise than to the extent to which the appended claim restricts me.

25 I claim:

In a hot air heating system for buildings, the combination of an air recirculating and a pipeless system, comprising a furnace, having an outer casing, an inner casing and

an air thoroughfare therebetween, means 30 forming a vertical warm air conduit therefrom, a register directly above said conduit, means forming a cool air conduit about said warm air conduit, warm air pipes 35 extending laterally and then vertically from said furnace through the partition walls of the building, cool air ducts paralleling the outer casing of said furnace and in spaced relation thereto, connections between said ducts and the base of said 40 furnace and with the cool air conduit from the said register, whereby cool air is admitted to said thoroughfare, extensions to said ducts extending laterally and then vertically through the partition walls of the 45 building, means to admit air from the floor levels of the rooms in said buildings and from the outside thereof, to said extensions whereby the cool air descends through said ducts to said thoroughfare and is heated 50 therein by radiation from the inner casing of said furnace and ascends through the said hot air pipes and the conduit from said furnace and means to regulate the direction and volume of the flow of the ascending 55 warm air, substantially as described.

In testimony whereof I affix my signature.

CHARLES McVEETY.
